UNITED STATES PATENT OFFICE.

LEROY G. BINKLEY, OF CHICAGO, ILLINOIS, ASSIGNOR TO RAILWAY & MINE SUPPLY COMPANY, OF CHICAGO, ILLINOIS, A CORPORATION OF ILLINOIS.

MINE-CAR WHEEL.

1,329,496.

Specification of Letters Patent. Patented Feb. 3, 1920.

Application filed September 26, 1918. Serial No. 255,747.

To all whom it may concern:

Be it known that I, LEROY G. BINKLEY, a citizen of the United States, residing at Chicago, in the county of Cook and State of Illinois, have invented certain new and useful Improvements in Mine-Car Wheels, of which the following is a specification.

This invention relates in general to rolling stock and more particularly to the wheels 10 and their manner of attachment on mine cars.

Owing to the sharp curves of the tracks and the irregularities in the track bed in mines it has been found practically necessary to mount each wheel of a mine car so that it is independently rotatable on its axle. Various constructions have been employed for attaching the wheels to the axles or to the bearing boxes so as to prevent longitudinal 15 displacements of the wheels in case of derailment of the car.

My present invention is concerned more particularly with the attachment of the car wheel to its axle so that it will not become 20 longitudinally displaced in case of derailment or other accident to the car, the primary object of the invention being to produce a locking connection for the wheel which will maintain the wheel in position 25 during operation and which can be released so as to readily permit the removal of a wheel and its replacement by another whenever occasion requires, such for instance, as the breaking of a wheel itself.

Another object of the invention is to provide a car wheel and its mounting which shall be simple in construction, strong and durable in operation, which will protect the 30 wheel bearing against the entrance of dust and dirt, and which when the wheel is removed will so retain the bearing rollers that they will not become disassociated from their bearing raceway or be free to drop out on to the dirty floor of the mine.

Other objects and many of the attendant 35 advantages of my invention should be readily appreciated by those skilled in the art as the same becomes better understood by reference to the following description when 40 considered in connection with the accompanying drawings.

Referring to the drawings:

Figure 1 is a longitudinal sectional view through a car wheel and its mounting embodying one form of my invention;

55

Fig. 2 is a transverse sectional view taken substantially on the line 2—2 of Fig. 1;

Fig. 3 is an end view looking at the inner end of the wheel hub; and

Fig. 4 is a view similar to Fig. 1 of a modified form of my invention.

By reference to the drawings it will be observed that reference character 5 indicates generally a fragment of a car body to which the bearing boxes 6 are securely bolted in the customary manner, the bolt holes through which the fastening bolts pass being indicated by reference character 7. This box, as will be observed from Fig. 1, is cored longitudinally to accommodate the axle 8 and the outer end of the core is enlarged to receive the hub of the wheel, the inner end of the enlargement being extended into a circumferential groove 9 for a purpose which will be later explained.

75

The axle 8 extends through the bearing box and, as will be understood, also extends entirely across the car and through the companion bearing box on the opposite side of the car body where it receives the other 80 wheel. It is thought, however, that an illustration of a box and its coöperating parts at one side of the car will be sufficient for an understanding of this invention. The smaller portion of the bearing box core is 85 sufficiently larger than the shaft 8 to accommodate a sleeve 10 which snugly fits the shaft 8 and is rigidly secured thereto by a pin 11, as shown.

The sleeve 10 at its inner end is provided 90 with a radial flange 12, best shown in Fig. 2, which has formed integrally therewith and projecting radially therefrom a plurality of lugs 13 spaced unequal distances apart around the periphery of the flange.

95

The wheel, designated generally by reference character 14, is provided with a hub 15 adapted to extend into the enlarged core of the bearing box and to rotate loosely therein. The inner end of the hub is provided with 100 an internal circumferential groove 16 adapted to receive the lugs 13 of the sleeve 10, and

the inwardly projecting flange 17 disposed in the groove 9 of the bearing box is provided with a plurality of longitudinally extending slots 18 corresponding in number and spacing to the lugs 13 on the sleeve 10. It will be manifest that when the wheel is positioned so that each of the slots 18 is in longitudinal alinement with its respective lug 13 the wheel may be slid longitudinally 10 into position on the axle whereupon a slight rotary movement of the wheel will cause the lugs 13 to engage behind the flange 17, thus locking the wheel against longitudinal displacement in all positions except one, where 15 the lugs and slots are disposed in absolute longitudinal alinement with each other. During the operation of the car the possibility of an end pull upon a wheel at the exact instant that the lugs and slots are 20 in alinement, so as to permit removal of the wheel, is infinitely remote, and consequently the wheel is for practical purposes securely locked to its bearing box against longitudinal displacement, while at the same time 25 by having suitable marks upon the box and its wheel by which the wheel may be positioned to aline the slots and lugs ready removal of the wheel when occasion requires is possible.

30 Between the inner end of the hub 15 and the bottom of the groove 9 in the bearing box there is interposed a bearing washer 19 adapted to receive the inward end thrust of the wheel and since the outer end of the 35 axle terminates short of the inner face 21 of the wheel hub no end thrust is imparted to the axle but all end thrust is delivered directly to the bearing box through the washer 19. It should also be noted that the 40 unequal spacing of the lugs and their companion slots makes it impossible for the wheel to be removed except when it has been rotated to one definite position. Were the slots and lugs spaced equal distances apart 45 the wheel might be removed in any one of three positions, which of course would increase the liability of accidental displacement.

In order to reduce the friction of rotation 50 of the wheel to a minimum I have interposed between the axle and the wheel, roller bearings comprising a series of bearing rollers 22. The inner ends of these rollers are mounted in an annular raceway 23 formed 55 on the outer face of the flange of the sleeve 10, while their outer ends are mounted in a raceway formed in a ring 24 shrunk upon the outer end of the axle 8 or pinned thereto or secured in any preferred 60 manner. A steel housing 25 is fitted snugly within the hub of the wheel and surrounds the bearing rollers. When the wheel is removed this housing is removed with the wheel and the bearing rollers remain 65 in position on the projecting portion

of the axle, where they may be inspected or repaired, if necessary, without any liability of their dropping out upon the dirty floor of the mine.

In Fig. 4 I have shown a slightly different 70 mounting for the bearing rollers in which the sleeve 10 is extended outwardly approximately to the end of the axle providing a bearing sleeve 26 terminating at its outer end in a radial flange 27 provided with a 75 raceway for the outer ends of the bearing rollers 22, their inner ends being mounted similarly to what has previously been described in connection with Fig. 1. In this instance, however, the flange 27 being 80 integral with the sleeve extension 26, cannot be removed for replacement of bearing rollers, consequently at one point the raceway is provided with a radial extension 28 through which the outer ends of the rollers may be 85 introduced into the raceway proper in this flange 27. It will be manifest that in assembling the rollers the inner end of each roller is introduced into the raceway at the inner end of the bearing portion of the hub, the 90 wheel of course at this time being removed, whereupon the outer end of the roller is dropped through the groove or extension 28 into the raceway in the flange 27. All of the rollers may be assembled one at a time 95 in this manner.

It will be manifest from the foregoing that I have provided in my car wheel a mounting in which the bearing rollers are always maintained in position on the axle 100 when the wheel is removed, that the removal and replacement of a wheel may be quickly and easily accomplished when the wheel is properly alined with respect to its box, and that the overlapping relation of 105 the box and inner end of the wheel hub protects the bearings against the entrance of dust and dirt which would cause them to wear rapidly and decrease their longevity.

While I have shown and described those 110 embodiments of my invention which at present seem preferable, it should be understood that the structure shown and described is capable of considerable modification and variation without departing from the essence 115 of the invention as set forth in the following claims.

I claim:

1. In a mine car wheel, the combination of a bearing box, an axle projecting there-through, a sleeve disposed within said box and secured to said axle, a wheel journaled on the projecting end of the axle, and means for detachably securing the hub of said wheel to said sleeve so as to hold the wheel 120 against longitudinal displacement.
2. In a mine car wheel, the combination of a bearing box, an axle therefor, a sleeve secured to the axle and projecting within the box, a wheel journaled on said axle, and co- 130

operating elements carried by said sleeve and the hub of said wheel, whereby said hub is detachably locked to the sleeve against longitudinal displacement from the axle.

5 3. In a mine car wheel, the combination of a bearing box, an axle, a sleeve surrounding the axle within the box and provided at its inner end with radially projecting locking elements, and a wheel journaled on said 70 axle, the hub of said wheel being provided with locking elements adapted to coöperate with said locking elements on the sleeve to hold said wheel in position.

10 4. In a mine car wheel, the combination of a bearing box, an axle, a sleeve within said box surrounding said axle and provided with radially projecting locking lugs, a wheel journaled on said axle, and a flange carried by the inner end of the wheel hub 80 adapted to coöperate with said lugs to hold said wheel in position, said flange being provided with slots through which said lugs may pass into locking relation with said flange.

15 5. In a mine car wheel, the combination of a bearing box provided at its outer end with an enlarged core adapted to receive the hub of a wheel, a groove formed at the inner end of said enlarged core, a thrust bearing washer interposed between the bottom 90 of said groove and the inner end of a wheel hub, an axle projecting through said box, a wheel mounted on said axle, and means secured to the axle and projecting within 100 said bearing box into interlocking relation with said wheel hub to maintain said wheel in position.

20 6. In a mine car wheel, the combination of a bearing box, an axle, a wheel journaled upon the outer end of said axle, bearing rollers disposed between said wheel and axle, and a sleeve secured to the axle, said sleeve being provided with means for locking said wheel against longitudinal displacement and with means for maintaining said bearing rollers in position on said axle when the wheel is removed.

25 7. In a mine car wheel, the combination of a bearing box, an axle projecting therethrough, a wheel journaled on said axle, and means within but structurally independent of said box for locking said wheel to the axle against longitudinal displacement therefrom, said means including a flange 110 carried by and projecting radially from said axle.

30 8. In a mine car wheel, the combination of a bearing box, an axle projecting therethrough, a wheel journaled on said axle 115 with its hub extending into said box, and means disposed entirely within the perimeter of said hub for detachably locking said wheel to said axle within said box.

35 9. In a mine car wheel, the combination of a bearing box provided at its outer end

with an enlarged core, an axle projecting through said box, a wheel journaled on said axle with the inner end of its hub extending into said enlarged core, and means independent of said box for securing said inner end 70 of the wheel hub to the axle to prevent displacement of said wheel relatively to said axle, said means including a flange projecting radially from said axle.

10 10. In a mine car wheel, the combination 75 of an axle, a bearing box and a wheel disposed on said axle in overlapping relation, and means disposed within the body of said box comprising engaging elements carried by said wheel and axle respectively within 80 the perimeter of said hub whereby the wheel is rotatably attached to the axle.

15 11. In a mine car wheel, the combination of an axle, a bearing box and wheel hub disposed thereon in telescopic relation, and 85 means carried by said axle and engaging the telescoping portion of said hub for rotatably locking said hub to said axle.

20 12. In a mine car wheel, the combination of an axle, a bearing box and wheel hub 90 disposed thereon in telescopic relation, and means including a flange projecting laterally from the axle within said box and means on said hub coöperating with said flange for rotatably locking said hub to said axle. 95

25 13. In a mine car wheel, the combination of an axle, a bearing box and a wheel hub disposed thereon in telescopic relation, and means including a shoulder on said hub within said box and means on said axle co- 100 operating with said shoulder for rotatably locking said hub to said axle.

30 14. In a mine car wheel, the combination of an axle, a bearing box and a wheel hub disposed thereon in telescopic relation, and 105 means including shoulders carried by said axle and said hub within the box for rotatably locking said hub to said axle.

35 15. In a mine car wheel, the combination of an axle, a bearing box and a wheel hub 110 disposed thereon in telescopic relation, and means including a sleeve carried by the axle and having a shoulder disposed within said box for rotatably locking said hub to said axle. 115

40 16. In a mine car wheel, the combination of an axle, a bearing box and a wheel hub disposed thereon in telescopic relation, a sleeve secured on said axle, and means including a shoulder within the box on said 120 hub and coöperating with said sleeve for rotatably locking said hub to said axle.

45 17. In a mine car wheel, the combination of a bearing box, an axle, a sleeve on said axle provided with a plurality of radially 125 disposed flanges arranged in spaced relation, a wheel provided with a hub surrounding said sleeve and flanges, and bearing rollers interposed between said sleeve and said hub, said flanges being provided with raceways to 130

accommodate and retain the ends of said rollers whereby the rollers are retained in position on the axle upon removal of the wheel.

- 5 18. The combination of a mine car wheel, an axle projecting into the hub of said wheel, a sleeve on said axle provided with

radially disposed flanges arranged in spaced relation, and bearing rollers disposed between and retained in position by said flanges so that the rollers are retained in position on the axle upon removal of the wheel.

L. G. BINKLEY.
